(76) Inventor: **Lemuel Adams**

Samuel Adams, Redding Conn.
Setters Patent

The Schedule referred to in this Setters Patent and making part of the same
containing a description in the words of the said Samuel Adams himself
of his improvement in the art of Cutting Corn teeth

To all to whom these presents shall come -

Be it known that I Samuel Adams of Redding in the County of Fairfield in the
State of Connecticut have invented a new and useful improvement in the art
of Cutting Corn teeth which substitutes power for manual labor and that the
following is a full and exact description thereof. It consists of a shaft or axle of
suitable length with bearings for it to revolve upon also a pulley revolve upon
the axle the nose of which is through which the axle passes is of sufficient length
on one side to admit of catches which are made straight upon one side and
slanting upon the other until the space between them comes to a point at the
bottom. The other end of said nose is of sufficient length to admit of a groove
channel to be formed around it for a belt to run in and not interfere with the
surface of the pulley or the belt which runs upon the said pulley. There is also a
collar equal in diameter to the nose of the pulley the said collar has a slot to receive
a fit there up the axle described nose the collar is made fast upon the aforesaid
named axle with keys. There is also a shoulder around the axle a short distance
from that part of the axle in which the channel is formed. There is likewise a
long neck of which is made to fit the channel in the nose of the pulley. This
neck is fastened by a pin through it one third of its length distant from the said
nose which is fitted to the channel. The other end is joined to a rod which
extends in the same direction with the axle and the other end of the rod is ad-
mitted by a joint to a square of which one end is longer than the other. The rod
is attached to the shorter end of the square the said square is placed upright
directly under a bench that the cutting machine stands upon and is made
fast to the bench at its angle corner by a hinge another rod is also attached by
a joint to the longest end of the square which rod extends upwards by the

opposite side of the bench and over it is placed a hand piece one end of which operates as a lever upon the last mentioned rod and the other end is fastened to the bench by a hinge under the hand piece between the kings and the tail rod is a strong wire spring directly over the hand piece is a thrust piece placed upright the bottom end projecting backwards sufficiently for the hand piece to rest under it. The said thrust piece is fastened by a pin through the center a spring is also placed behind the thrust piece below the pin. The ^{invention} of the above described may be appreciated by understanding that the usual method of cutting comb teeth is by manual labor. Whilst by applying this invention to a brick comb cutting machine the work is performed by power. The application may be made by uniting the foregoing described angle with the angle of the cutting machine by a connector whilst the above mentioned hand piece rests under the thrust piece the cutting teeth upon the face of the pulley and these upon the collar are eliminated and the pulley revolves upon the axles between the shoulders and the collar, but by a slight pressure upon the hand piece the hand piece is forced upward by the spring which is under it. Whilst the hand piece rests under the thrust piece these upon the collar and the work is carried with the pulley likewise by a slight pressure upon the hand piece it is forced under the thrust piece which again eliminates the cutting teeth and the work instantly ceases but the pulley continues to revolve.
